UNITED STATES PATENT OFFICE.

SENECA G. LEWIS, OF GREENSBURG, PENNSYLVANIA.

TENNIS-RACKET AND THE LIKE.

1,279,719.

Specification of Letters Patent. Patented Sept. 24, 1918

Application filed November 20, 1916. Serial No. 132,270.

To all whom it may concern:

Be it known that I, SENECA G. LEWIS, residing at Greensburg, in the county of Westmoreland and State of Pennsylvania, a citizen of the United States, have invented or discovered certain new and useful Improvements in Tennis-Rackets and the like, of which improvements the following is a specification.

10 My invention consists in a new article of manufacture: stringing for rackets and like articles, made essentially of wire and coated with rubber.

Piano wire consists of a strand of wire, 15 gut, or fiber (ordinarily silk) forming a core or heart, surrounded and incased in a helical wrapping of fine wire (ordinarily steel wire). This article is used not only, as its name imports, in the stringing of pianos; 20 it is used in stringing various musical instruments: violins, for example, and guitars.

The addition to such a wire of a rubber coating must have the effect, so far as concerns use in musical instruments, of modifying the tone and dampening vibration; but it is with new uses of the article, modified in structure in the manner indicated, that I am chiefly concerned. I have found that piano wire coated with rubber is useful 25 as material for stringing tennis rackets, lacrosse sticks, snow shoes, and such like articles; and manifestly being useful in such applications, it has the advantage of greater durability over the catgut commonly used 30 for this purpose.

I prefer to employ piano wire, that is to say wire built up of a central body of wire or of fibrous material and a closely wrapped helix of fine wire, but, manifestly, plain wire 40 or a compound braided or stranded wire may be coated with rubber, and when coated may be rendered serviceable (as bare wire is not) for uses such as those indicated.

The rubber coating which characterizes 45 my invention may be applied to the wire in the form of thin sheets or strips wrapped either upon the component strands individually before braiding twisting or wrapping or upon the assembled and otherwise com-

pleted article; or it may, and preferably will be applied by causing the wire (either the strand or the otherwise completed article) to pass through a liquid solution of rubber. The solvent for the rubber in such case will be such as desired: bisulfite of carbon, chloroform, ether, naphtha, or another solvent. The strength of the solution and its fluidity or viscosity will be adapted to afford a coating of desired thickness upon the wire advancing through it. As the coated wire 55 passes from the bath, it may pass between wiping and spreading instrumentalities such as desired—between rolls, for example, or through a die-block. The article will, after being coated preferably be supported and disposed in such position and arrangement and subjected to such conditions as to allow the rubber of the coating to become air-cured. And, it will be understood that, air-curing being in contemplation, the initial 60 rubber preparation in solution (or in sheet form) will be compounded with that end in view. If it be a single strand that has been coated, the coated strand may be used as it is, or it may be further fabricated by braiding, twisting, wrapping, etc., these being operations familiar in the making of composite wire.

My invention is illustrated in the accompanying drawings, in which Figures 1 and 2 80 show two forms of coated wire and Fig. 3 shows a face view of a tennis racket equipped with my improved stringing.

In Fig. 1, there is shown a piano wire, comprising as explained above, a core 1 and a wrapped-on helix of flexible wire 2. In this instance the rubber-coating is in the form of thin sheets or strips 3, wrapped upon the wire helix 2.

In Fig. 2, there is also shown a piano wire, 90 comprising a core 1 and a wrapped-on helix of wire 2. In this form of stringing the rubber coating 4 illustrates such coating as results from passing the piano wire through a liquid solution of rubber as already explained.

I claim as my invention:

1. A tennis racket or the like comprising

a frame strung with an interwoven stringing. In testimony whereof I have hereunto set
consisting of a flexible wire coated with rubber. my hand.

SENECA G. LEWIS.

2. A tennis racket or the like comprising
5 a frame strung with an interwoven stringing
consisting of a core, a wrapped-on helix of
wire and a coating of rubber.
